OPERATOR FOR OVERHEAD DOORS

George W. Hahn, Dallas, Tex.

Application March 19, 1952, Serial No. 277,405

8 Claims. (Cl. 318—264)

1

This invention relates to door opening means and more particularly to a power operated mechanism for opening and closing doors such as are used upon garages and similar buildings.

Garages and similar buildings are often provided with upward opening doors which are mounted on a track controlling their movement. Such doors are usually balanced by springs or otherwise in order that the force needed to move the doors in one direction may be substantially equal to the force needed to move the door in the opposite direction. Power operated mechanisms for opening and closing such doors must be provided with control means to insure that the movement of the door in either direction is stopped and the power mechanism is deenergized if the door encounters an obstruction and that the direction of movement of the door is reversed upon reenergization of the power mechanism. Moreover, the power mechanism and the apparatus for controlling the power mechanism should be of simple and rugged construction and sufficiently light in weight to permit their suspension from the ceiling of a door.

Accordingly, it is an object of the invention to provide a new and improved power mechanism for opening and closing doors.

It is another object of the invention to provide a new and improved power mechanism for opening and closing upward opening doors of garages or the like.

It is still another object of the invention to provide a new and improved control means for power operated doors to stop the movement of the door if an obstruction is encountered by the door.

It is a further object of the invention to provide a new and improved control means for power operated doors to stop the movement of the door if an obstruction is encountered by the door and to reverse the direction of movement of the door when the door is next moved.

Briefly stated, the new and improved power operated mechanism and control means therefor comprises a reversible electric motor which is connected through a sprocket driven flexible member to a carriage slidably mounted on a channel shaped overhead rail. The carriage is connected to a door mounted for upward movement by means of a drawbar. The sprocket is connected to the motor through an overload release mechanism which disconnects the sprocket from the motor upon the obstruction of the movement of the door and at the same time actuates a switch control means which stops the

2

motor and insures that the direction of rotation of the motor will be reversed the next time the motor is started.

For a better understanding of the invention, reference may be had to the following description taken in connection with the accompanying drawing and its scope will be pointed out in the appended claims.

In the drawings:

10 Figure 1 is a vertical sectional view of a building having an upwardly opening door provided with the power operated mechanism of the invention for opening and closing the door;

15 Figure 2 is a sectional view, taken on the line 2—2 of Figure 1, some parts being broken away to show details of the overload release mechanism;

Figure 3 is a fragmentary perspective view of the carriage in place on the overhead rail;

20 Figure 4 is a sectional view taken on the line 4—4 of Figure 1, some parts being broken away to show the details of the control means for stopping the motor and reversing its direction of rotation; and,

25 Figure 5 is a diagrammatic illustration of the electrical circuit of the control means for controlling the operation of the motor.

Referring now to the drawing, the upwardly opening door 10 of conventional design is formed of sections 11 connected by hinges 12. The door is mounted between channel shaped guides 13, only one of which is seen in Figure 1, which are of substantially inverted L-shape having an overhead horizontal portion 14 and a vertical portion 15. The door may also be provided with balancing means, such as springs, not shown.

The power operated mechanism for opening and closing the door 10 includes a channel shaped rail 16 on which is slidably mounted a carriage 17. The carriage 17 comprises a control portion 18 which is disposed between the flanges 19 and 20 of the rail 16, a slot 21 in which is received the flange 19, and a carriage flange 22 which extends parallel to but spaced from the web 23 of the rail. A pair of rollers 24 and 25 rotatably mounted on the carriage flange 22 by means of bolts 26 and 27, respectively, engage the web 23 to keep the carriage properly aligned on the rail.

50 A drawbar 28 has one end pivotally secured between a pair of depending ears 29 and 30 of a carriage by means of a pin 31 and has its other end pivotally secured to the upper portion of the door 10 in any suitable manner. It will be apparent that as the carriage 17 is moved back

and forth on the rail 16, the door 10 will move upwardly and then rearwardly between and on the rails 13 to open the door and forwardly and downwardly to close the door.

The carriage is moved by an endless flexible member 32 having a chain section 33 and a cable section 34. The chain section has one end secured to the central portion 18 of the carriage in any suitable manner and its other end is secured to one end of the cable section 34. The other end of the cable section 34 is secured to the ears 29a and 30a of the carriage by a pin 35. The cable section extends about a pulley 36 rotatably secured to the forward end of the rail 16 while the chain section 33 extends about a sprocket 37. The forward end of the rail 16 is secured to the garage above the door by a bracket 38 which is bolted to the garage and the forward end of the rail. The rear end of the rail is secured by bolts 39 and 40 to the flange 41 of an angle iron 42 whose flange 43 is secured by bolts 44 to the housing of a motor 45. The motor is rigidly mounted on the ceiling of the garage by means of a pair of channel shaped brackets 46 and 47 which are secured to the ceiling and the motor housing by bolts 48.

Portions of the flange 20 and the web 23 of the overhead rail 16 are removed as at 49 to permit the sprocket 37 to extend above the flange 20 and allow one end portion of the chain section 33 to move over the flange 20 toward the pulley 36, the other end portion of the chain section is always disposed between the flanges 19 and 20 of the rail.

The sprocket 37 is rotatably and slidably mounted on the shaft 50 of a speed reducing transmission 51 which is run by the drive shaft of the motor 45. The sprocket has a sleeve portion 52 provided with a pair of slots 53 into which are adapted to extend the cam sections 54 of a fixed collar 55 rigidly secured to the shaft 50 by a set screw 56. A free collar 57 is slidably disposed on the shaft 50 on the opposite side of the sprocket and is biased toward the sprocket by a spring 58 disposed about the shaft 50 between the free collar and a lock nut 60 on the threaded end 61 of the shaft 50. A set screw 62 may be employed to lock the nut 60 in any desired position on the shaft 50. It will be apparent now that the sprocket 37 and the free collar 57 are slidable away from the fixed collar 55 if the load or force tending to prevent the sprocket 37 from rotating rises above a predetermined value, the sprocket will stop rotating while the shaft 50 will continue to rotate. The cam sections 55 will cam the sprocket away from the set collar against the force exerted by the spring 58. By adjustment of the lock nut 60, the value of the load on the sprocket necessary to cause this disconnection or release of the sprocket from the shaft 53 can be set at any predetermined value. In effect, the spring, the free and fixed collars and the slidably sprocket constitute the overload release mechanism.

The motor 45 is disconnected from its source of power and stopped each time the sprocket 37 is cammed away by the fixed collar by an arm 63 having one end rigidly secured to the free collar 57. The arm 63 extends through suitable apertures in the web 23 of the rail 16 and the flange 41 of the angle iron 42 and also through suitable apertures in the flange 64 of the angle iron 65 and a side of a switch housing 66. The flange 67 of the angle iron 64 is secured to the motor housing by bolts 68. The switch housing is secured

to the flange 65 by welding or in any other suitable manner.

A pair of mechanically operated switches 68 and 69 are mounted in the housing 66 and are actuated by the adjustable screws 70 and 71, respectively, on a transverse arm 72 rigidly secured to the end of the arm 63 disposed in the switch housing.

The switch 68 is a normally closed microswitch which is opened by the screw 70 each time the sprocket 37 is cammed away from the fixed collar. The switch 68, when actuated, disconnects the motor 45 from the source of electric current and therefore stops the motor each time an overload is imposed on the sprocket 37. The switch 69 is a conventional switch which reverses the flow of current to the control windings of the motor 45 each time the motor is stopped. The switch 60 may be "Model #RC-100AR" made by the Guardian Electric Manufacturing Company which includes a rotary element 73 having a plurality of spaced slots 74 along its periphery. The rotary element is rotated a fixed distance each time the switch 69 is actuated by the screw 71. A cam 75 rides on the rotary element and moves three resilient leaves 76, 77 and 78 to which it is connected upwardly or downwardly as the rotary element is rotated step by step.

When the cam 75 is located in one of the slots or depressions in the rotary element 73, the contacts on the resilient leaves 77 and 78 are in the solid line portions shown in Figure 5 and cause current to flow in one direction through the conductors 79 and 80 to the control winding in the motor 45 to cause it to rotate in one direction. When the cam 75 is located on the periphery of the rotary element between a pair of slots, the resilient leaves 77 and 78 are in the broken line positions shown in Figure 5 and cause current to flow in the opposite direction through the conductors 79 and 80 to the control winding in the motor to cause it to rotate in the opposite direction. At the same time, the resilient leaf 76 causes the light bulb 81 to be connected to a source of current.

Assuming now that the garage door 10 is closed and the motor is not running, the sprocket 37 is cammed away from the fixed collar 55 and the screw 70 holds the switch 68 open. If the push button switch 82 is now closed momentarily, current will flow from the input terminal 83 through the conductor 84, the fuse 85, the conductor 86 to the terminal 87 of the motor, the main winding of the motor, from the terminal 88 of the motor through the conductors 89, 90 and 91, the push button switch 82, and conductor 92 to the input terminal 93. At the same time current will flow to the control windings of the motor from the input terminal 83 through conductor 84, fuse 85, conductors 94 and 95, resilient leaf 78, conductor 80, to the terminal 96 of the motor, the control windings, from the terminal 97 through the conductors 79 and 88, the resilient leaf 77, conductors 99 and 91, switch 82 and conductor 92 to the input terminal 93.

With current thus flowing through the windings of the motor, the motor will rotate causing the shaft 50 to rotate to bring the cam sections 54 of the fixed collar into alignment with the slots 53 of the sleeve 52 of the sprocket 37. The spring 58 now moves the sprocket, and the free sleeve 57, toward the fixed sleeve. The sprocket 37 will now rotate with the shaft 50. At the same time the arm 63 moves with the free sleeve 57 and

allows the switch 68 to close. The push button may now be opened but, since the switch 68 is connected across the terminal 93 and the conductor 91, current will continue to flow to the motor as described.

As the sprocket rotates, the chain section 33 is drawn in a clockwise manner about the sprocket, the carriage 17 is pulled to the left, Figure 1, and the drawbar 28 pulls the door upwardly and rearwardly to open the door. The carriage moves to the left either until it contacts the stop 108 on the rail 16 or until the door in its movement contacts an obstruction. The sprocket 37 will then cease to rotate and will be moved outwardly against the resistance of spring 58 by the cam sections 54 of the fixed collar. The arm 63 will move with the free collar and the screw 70 will open the switch 68 interrupting the flow of current to the motor 45 which will stop. At the same time, the screw 71 actuates the switch 69 and the rotary element 73 is rotated a predetermined distance so that the cam now rides on the periphery between a pair of slots 73. This causes the resilient leaf 76 to connect the light bulbs 81 across the input terminals 83 and 93, current flowing from the terminal 83 through the conductor 84, fuse 85, conductor 94, resilient leaf 76, conductor 101, light bulb 81, and the conductors 102 and 103 to input terminal 93. The light bulb will continue to burn until the door is closed.

If it is now desired to close the door, the push button switch 82 is closed and current is supplied as before to the terminals 87 and 88 of the motor 45 and therefore to its main windings. The direction of flow of current to the terminals 96 and 97, and therefore to the control windings, is reversed since the resilient leaves 71 and 76 are now moved to the broken line positions shown in Figure 5. Current will now flow from the terminals 83 through the conductor 84, fuse 85, conductors 94 and 95, resilient leaf 78, conductors 104 and 109 to terminal 97, the control windings and from terminal 96, conductors 80 and 105, resilient leaf 71, conductors 99 and 91, switch 82 and conductor 92 to input terminal 93.

Since the direction of flow of current in the control windings is now reversed, the motor will now rotate in the reverse direction and shaft 50 will rotate in a counter clockwise direction (Figure 1). When the cam sections 54 of its fixed sleeve become aligned with the slots 53 of the sprocket sleeve 52, the sprocket will move on the shaft 50 toward the fixed sleeve and will rotate therewith. The switch 68 will now close and the motor will continue to run, the carriage being moved to the right, Figure 1, and moving the door 10 toward closed position. This movement of the door will continue until it closes and hits the ground or until it contacts some obstruction. In that event again, the sprocket will move away from the fixed sleeve, the switch 68 will be opened by the screw 70 and the switch 69 will be actuated by the screw 71 to rotate the rotary element 73 another step to bring a slot 74 beneath the cam 75. Since the resilient leaf is now moved to the full line position, the light bulb 81 will go out. If the switch 82 is now closed again, the direction of rotation of the motor will again be reversed and the door will be moved to open position.

The motor 45 may be a single phase alternating current motor supplied with alternating current from the terminals 83 and 93 connected to any source of alternating current of the proper voltage.

It will now be apparent that a power operated

mechanism for opening upwardly opening doors has been provided which will open and close such doors and will automatically stop the movement of the door if an obstruction is contacted by the door. Moreover, it will be seen that each time the door is stopped while moving in one direction, it will begin moving in the opposite direction when the mechanism is again started. This insures that damage will not be caused either to the door or to the obstruction when the mechanism is again placed in operation.

It will also be apparent that the switch 82 may be located wherever desired and that if it is desired to control the door from more than one station, a plurality of push button switches, one at each station, may be connected in parallel with the switch 82. Moreover, the push button switch 82 may be replaced by a radio controlled relay or switch if desired.

Manifestly, the construction as shown and described is capable of some modification and such modification as may be construed to fall within the scope and meaning of the appended claims is also considered to be within the spirit and intent of the invention.

What is claimed is:

1. A power operated mechanism for operating upwardly opening doors comprising a reversible motor; a shaft driven by said motor; a first collar rigidly fixed to said shaft and provided with cam means; a sprocket rotatably and slidably mounted on said shaft; means yieldably biasing said sprocket into engagement with said collar whereby said sprocket normally rotates with said fixed collar and said shaft, said cam means disengaging said sprocket from said fixed collar upon the occurrence of an overload on said sprocket; a first switch means for disconnecting said motor from a source of current; a second switch means for controlling the direction of rotation of said motor, said second switch means reversing the direction of rotation of said motor each time it is actuated; and means operatively associated with said sprocket for actuating said first and second switch means each time said sprocket is disengaged from said fixed collar.

2. A power operated mechanism for operating upwardly opening doors comprising a reversible motor; a shaft driven by said motor; a first collar rigidly fixed to said shaft and provided with cam means; a sprocket rotatably and slidably mounted on said shaft; means yieldably biasing said sprocket into engagement with said collar whereby said sprocket normally rotates with said fixed collar and said shaft, said cam means disengaging said sprocket from said fixed collar upon the occurrence of an overload on said sprocket; a first switch means for disconnecting said motor from a source of current; a second switch means for controlling the direction of rotation of said motor, said second switch means reversing the direction of rotation of said motor each time it is actuated; a second collar rotatably and slidably mounted on said shaft between said biasing means and said sprocket; and means connected to said second collar for actuating said first and second switch means each time said sprocket is disengaged from said fixed collar.

3. A power operated mechanism for operating upwardly opening doors comprising a reversible motor; a shaft driven by said motor; a first collar rigidly fixed to said shaft and provided with cam means; a sprocket rotatably and slidably mounted on said shaft; means yieldably biasing said sprocket into engagement with said collar where-

by said sprocket normally rotates with said fixed collar and said shaft, said cam means disengaging said sprocket from said fixed collar upon the occurrence of an overload on said sprocket; a first switch means for disconnecting said motor from a source of current; a second switch means for controlling the direction of rotation of said motor, said second switch means reversing the direction of rotation of said motor each time it is actuated; means operatively associated with said sprocket for actuating said first and second switch means each time said sprocket is disengaged from said fixed collar; and a flexible member driven by said sprocket and connected to a door to move said door to open and closed positions.

4. A power operated mechanism for operating upwardly opening doors comprising a reversible motor; a shaft driven by said motor; a first collar rigidly fixed to said shaft and provided with cam means; a sprocket rotatably and slidably mounted on said shaft; means yieldably biasing said sprocket into engagement with said collar whereby said sprocket normally rotates with said fixed collar and said shaft, said cam means disengaging said sprocket from said fixed collar upon the occurrence of an overload on said sprocket; a first switch means for disconnecting said motor from a source of current; a second switch means for controlling the direction of rotation of said motor, said second switch means reversing the direction of rotation of said motor each time it is actuated; a second collar rotatably and slidably mounted on said shaft between said biasing means and said sprocket; means connected to said second collar for actuating said first and second switch means, each time said sprocket is disengaged from said fixed collar; and a flexible member driven by said sprocket and connected to a door to move said door to open and closed positions.

5. A power operated mechanism for operating doors comprising a reversible motor; a shaft driven by said motor; cam means rigidly secured to said shaft; a sprocket rotatably and slidably mounted on said shaft; means yieldably biasing said sprocket into locking engagement with said cam means whereby said sprocket normally rotates with said shaft, said sprocket moving on said shaft out of locking engagement with said cam means upon the occurrence of an overload on said sprocket; a first switch means for disconnecting said motor from a source of current; a second switch means for controlling the direction of rotation of said motor, said second switch reversing the direction of rotation of said motor each time it is actuated; and means operatively associated with said sprocket for actuating said first and second switch means each time said sprocket moves out of locking engagement with said cam means.

6. A power operated mechanism for operating doors comprising a reversible motor; a shaft driven by said motor; cam means rigidly secured to said shaft; a sprocket rotatably and slidably mounted on said shaft; means yieldably biasing said sprocket into locking engagement with said cam means whereby said sprocket normally rotates with said shaft, said sprocket moving on said shaft out of locking engagement with said

cam means upon the occurrence of an overload on said sprocket; a first switch means for disconnecting said motor from a source of current; a second switch means for controlling the direction of rotation of said motor, said second switch reversing the direction of rotation of said motor each time it is actuated, a collar rotatably and slidably mounted on said shaft between said biasing means and said sprocket; and means connected to said collar for actuating said first and second switch means each time said sprocket is disengaged from said fixed collar.

7. A power operated mechanism for operating doors comprising a reversible motor; a shaft driven by said motor; cam means rigidly secured to said shaft; a sprocket rotatably and slidably mounted on said shaft; means yieldably biasing said sprocket into locking engagement with said cam means whereby said sprocket normally rotates with said shaft, said sprocket moving on said shaft out of locking engagement with said cam means upon the occurrence of an overload on said sprocket; a first switch means for disconnecting said motor from a source of current; a second switch means for controlling the direction of rotation of said motor, said second switch reversing the direction of rotation of said motor each time it is actuated; means operatively associated with said sprocket for actuating said first and second switch means each time said sprocket moves out of locking engagement with said cam means; and a flexible member driven by said sprocket and connected to a door to move said door to open and closed positions.

8. A power operated mechanism for operating doors comprising a reversible motor; a shaft driven by said motor; cam means rigidly secured to said shaft; a sprocket rotatably and slidably mounted on said shaft; means yieldably biasing said sprocket into locking engagement with said cam means whereby said sprocket normally rotates with said shaft, said sprocket moving on said shaft out of locking engagement with said cam means upon the occurrence of an overload on said sprocket; a first switch means for disconnecting said motor from a source of current; a second switch means for controlling the direction of rotation of said motor, said second switch reversing the direction of rotation of said motor each time it is actuated, a collar rotatably and slidably mounted on said shaft between said biasing means and said sprocket; means connected to said collar for actuating said first and second switch means each time said sprocket is disengaged from said fixed collar; and a flexible member driven by said sprocket and connected to a door to move said door to open and closed positions.
